DISHED STAR KITE

Monroe D. Johnson, Jr., 4620 Oregon Trail, and Warren
A. Tuckness, 1007 W. Virginia, both of Amarillo, Tex.

Filed Oct. 5, 1964, Ser. No. 82,027

Term of patent 14 years

(Cl. D34—15)

FIG. 1

FIG. 2

FIG.5

FIG.4

FIG.6

FIGURE 1 is a top plan view of a dished star kite shown in FIGURE 2;

FIGURE 2 is a front elevational view of a dished star kite showing our new design;

FIGURE 3 is a left side view of the kite of FIGURE 2;

FIGURE 4 is a left front oblique view of the kite of FIGURE 2;

FIGURE 5 is a left rear oblique view of the kite of FIGURE 2; and

FIGURE 6 is a rear view of the kite of FIGURE 2.

We claim:

The ornamental design for a dished star kite, as shown.
